CARBOY CONTAINER

Harry R. Gardner, Rahway, N. J., assignor to The Greif Bros. Cooperage Corporation, Cleveland, Ohio, a corporation of Delaware

Application December 27, 1948, Serial No. 67,338

4 Claims. (Cl. 217—52)

1

This invention pertains to a container for carboys of glass or the like in which may be sealed a desired liquid such as an acid. More particularly the present container is designed to afford a substantial protection to the enclosed carboy during storage, handling, and/or shipping. The container is in the form of a cylindrical drum, and the improvements which are special to this invention reside in the means whereby the carboy is sustained in a floating mounting while maintained centrally within the container in spaced relation to its walls. The protection thus afforded to the carboy is outstanding.

A suggestive embodiment of this invention is set forth in the accompanying drawings wherein—

Figure 1 is a view in perspective of the container as it appears when righted with the enclosed carboy properly secured therein;

Fig. 2 is a longitudinal section through the container, showing its initially inverted position, and that of the carboy, as when the latter has just been placed within the former;

Fig. 3 which is a view similar to Fig. 2 shows the container, with enclosed carboy, in upright position, as when assembly has been completed; and

Fig. 4 is a transverse section taken on line 4—4 of Fig. 2, but with the carboy removed from the view.

In the construction shown, I utilize a cylindrical container of plywood or the like having a body B which is initially open at both ends, the meeting edges of the body being joined as by a strip 10. Fitted within the body adjacent its lower end is a circular outer stay 11. This stay may be secured in place by fastenings 12 such as staples which pass therethrough and through the container body and on through a hoop 15 which surrounds the body adjacent its lower end. The stay and hoop thus assembled permanently upon the container body at its lower end also provide therefor a desirable reenforcement.

The top edge of the stay constitutes a support whereon may be rested a circular bottom head 17 for the container. This also may be conveniently produced from plywood and be reinforced transversely with a cleat 18 which is fixedly secured in place. A second inner stay 19 is also applied to the interior of the container body to engage the top face of the bottom head 17. As by means of staple fasteners 20 which traverse the inner stay 19, the container body, and the outer hoop 15, a further reen-

2

forcement is provided for the container adjacent its lower end, and also a stop for the bottom head 17 such that it is secured immovably in place between the inner and outer stays 19 and 11.

A top head 23 for the container is also provided. Such a head, which may be produced from plywood with transverse reenforcement provided by a cleat 24, is closely fitted within the container body close to its top. Inner and outer stays 25 and 26, respectively, are affixed within the container on opposite sides of the top head 23 for engagement therewith, the inner stay being secured in place as by staple fasteners 27 and the outer stay by fasteners 28, each set of fasteners passing also through the container body and then on through a reinforcing hoop 30 which is fitted closely around the body adjacent its upper end.

Initially the outer stays 26 and 11 remain disassembled and the bottom head 17 is also left out of the container; the top head, however, may be loosely fitted in place. Within the container, toward its top end, there is positioned a third head 32 which serves as a transverse brace. This intermediate head is fixedly secured in place between upper and lower stays 33 and 34 which are affixed to the container body as by staple fasteners 35. An opening 36 is formed centrally of the brace head for a purpose which will presently appear. Extending between the brace head 32 and the bottom head 17, and confined thereby against axial movement, is a shell S which constitutes an important feature of this invention. Desirably this shell is produced from plywood, and its meeting edges remain free, disconnected, and slightly spaced (see Fig. 4).

A container-shell assembly, as just described, is adapted to receive therewithin a carboy C. Such a carboy, best shown in Figs. 2 and 3, is usually made of glass or like material for the retention of acids, chemicals, etc. Its bottom b is flat, its sides s cylindrical although inclining inwardly near the bottom, and near the top its sides are extended inwardly to provide sloping shoulders t which merge with an upwardly extending neck n that joins with a collar c. A stopper, such as a cork x, is fitted into the open mouth of the carboy to provide a seal for the contents thereof. When the carboy is placed within the container, both are in inverted positions, as per Fig. 2, and when advanced axially therein the carboy collar and neck will be free to enter the opening 36 of the brace head 32. If advanced too far, the brace head will serve as a stop from which the carboy will later recede in

response to gravity when the container is righted.

For partial protection of such a carboy within the container, I utilize at the bottom one or more cushion pads 40 of cork or the like. Desirably three such pads, each in the form of a block, are pre-assembled with the bottom head 17 to which they may be fixedly secured as by glue at points equidistantly apart adjacent its periphery (see Figs. 2 and 3). These cushion pads provide full protection for the carboy at its bottom. Assembly of the bottom head 17 with the container follows placing of the carboy therewithin and, when done, the container is righted so that the carboy may then rest upon the cushion pads 40 which are carried by the bottom head 17.

The shell S is preferably made of plywood which, with the aid of heat and pressure, is bent to a substantially cylindrical form. The circumferential extent of the present shell is such that it will substantially surround the cylindrical side walls of the carboy, and its two free edges which lie in proximate relation will, in commercial practice, either overlap slightly, remain in light butt engagement, or remain slightly apart. This point is not important. It is a characteristic of such a plywood shell that it seldom retains a true cylindrical contour. When relaxed, it may be flat in one spot, humped in another, and so on, although following a generally curved contour. Furthermore, such a shell, if made of plywood, is endowed with a high degree of resilience, i. e. it may be flexed inwardly or outwardly in response to pressure, but when that pressure is withdrawn, the shell will tend to restore itself to its former contour. While this might be a disadvantage for certain uses, I find it highly important and advantageous for the present invention as will shortly be made apparent.

The shell, in a substantially relaxed condition, is pre-assembled with the container before the carboy is fitted in place. The two stays 19 and 34 which engage the shell at points near its opposite ends, are of substantial thickness, perhaps a quarter of an inch, so as to support the shell inwardly of the container body and in spaced relation thereto for the entire length of the shell. The body B of the container is relatively close to a true cylindrical form as a result of circular shaping forces that are applied thereto by the top and brace heads 23 and 32, and later by the bottom head as well. As a consequence, the shell S when fitted into place will be constrained to adjust its contour so as to further approach circularity, if its shape be excessively off-circular.

As will be observed clearly from Fig. 2, the cylindrical side walls of the carboy C are, from end to end (except for the inclined portion near its bottom), engaged with the surrounding shell which at every point opposite the carboy is free to expand outwardly against the tension of its own body. In so doing, the shell may flex somewhat into the annular space which intervenes between itself and the surrounding walls of the container body. The tendency of the shell to restore itself to its normal condition, as suggested in Fig. 2, will cause the shell to remain in pressure engagement with the carboy and maintain the same axially centered with respect to the container. I thus provide, in effect, a floating mounting wherein the carboy is sustained. The spring cushion afforded by this mounting extends continuously around the cylindrical side walls of the carboy, and has capacity for flexing radially outward in any direction, and against a resistance which is substantially uniform at

every point, so that the carboy is protected to the fullest possible extent.

Normally during handling, storage, and shipment, the container is stood on its bottom, as shown in Fig. 3. The bottom of the carboy is then supported upon the cushion pads 40 which may be of any suitable material for this purpose, natural cork being suggested as appropriate and adequate. It is unnecessary that the brace head 32 engage the carboy, for the reason that the frictional engagement which obtains between the carboy and the surrounding shell is very substantial, and normally sufficient to prevent axial movement of the carboy upwardly within the container.

When the carboy is opened up for use, the stay 26 is removed, thereby freeing the top head 24 so that it may be lifted out of the container. This exposes the stopper x at the top of the carboy. Removal of the stopper then follows to permit pouring of the liquid contents into or out of the carboy.

The construction which I have described is one which will meet export requirements in that the upper end of the carboy, including its stopper, is completely enclosed. For domestic purposes, such a complete enclosure is not necessary, and in that event the upper end of the container will terminate just above the stay 33, so that the brace head 32 then serves as a top head for the container.

Plywood drums have definite advantages in the way of lightness, resiliency and strength, and these factors can be controlled within wide limits by the thickness and number of the plies, and otherwise; the same is true of the inner shell which I employ as a cushion support for the carboy. For these reasons the container of my invention will adequately meet all the usual protecting requirements and tests by an ample margin. And it is further advantageous in that it is relatively inexpensive to construct, it permits a facile assembly of a carboy (or replacement thereof), and the few separate pads which are used may be pre-assembled with the bottom head so as to avoid separate handling.

I claim:

1. A container for a carboy comprising a cylindrical plywood drum wherein is secured an apertured head of circular form extending transversely thereof at a point remote from the bottom end of the drum, the circular head being in pressure engagement with the drum walls circumferentially to assure circularity thereof, a pair of spaced circular stays affixed to the drum interiorly thereof, one abutting the head on its under side to afford support thereto and the other at a point near the bottom end of the container, a bottom head affixed to the drum in abutting relation to the lower stay and engaging circumferentially with the drum to assure circularity thereof, and a circumferentially continuous resilient plywood shell of generally circular form, fitted within the drum to lie inwardly of the two stays and wholly between the two heads therewithin for axial confinement thereby, the meeting edges of the shell being disconnected to permit circumferential expansion of the shell outwardly into the annular space defined by the inner faces of the drum and the two stays, the shell diameter internally being fixed by the surrounding circular stays and being such that, when outwardly engaged with the spacer stays, it will inwardly engage the cylindrical walls of the carboy with 75 pressure, and the shell being free to expand out-

wardly between the stays into the space between itself and the walls of the cylindrical drum while exerting constant tension upon the carboy walls tending to float the carboy in an axial position within the container.

2. A container for a carboy or the like comprising a cylindrical body, a circular head secured to the bottom end of the body and an apertured head secured therein near its opposite end, a plywood shell of circular form having disconnected edges fitted within the container between the two heads for axial confinement thereby, a pair of stays spaced lengthwise of the container and secured thereto interiorly thereof and outwardly of the shell to provide spacers therefor, a cushion pad rested on the container bottom and adapted to engage the bottom end of the carboy when fitted therewithin and within the shell, the diameter of the shell being such that, when outwardly engaged with the spacer stays, it will inwardly engage the cylindrical walls of the carboy with pressure, and the shell being free to expand outwardly between the stays into the space between itself and the walls of the container body while exerting a constant tension upon the carboy walls tending to float the carboy in an axial position within the container.

3. A container for a carboy or the like comprising a cylindrical body, a circular head secured to the bottom end of the body and an apertured head secured therein near its opposite end, a resilient shell of sheet material of irregular circular form fitted within the container between the two heads for axial confinement thereby, spacer means spaced lengthwise of the container and secured thereto interiorly thereof and outwardly of the shell to space the latter from the container, the diameter of the shell being such that when outwardly engaged with the spacer means it will inwardly engage the cylindrical wall of the carboy with pressure, the ends of the sheet material of the shell being disconnected and said shell being free to expand outwardly between the spacer means into the space between itself and the walls of the container body in any radial direction while exerting a constant tension upon the carboy walls tending to float the

carboy in an axial position within the container, and a cushion pad rested on the container bottom and adapted to engage the bottom end of the carboy when fitted therewithin and within the shell.

4. A container for a carboy or the like comprising a cylindrical body, a bottom head affixed to the body, an apertured head affixed to the body at a point remote from the bottom head, a circumferentially continuous resilient plywood shell of approximately circular shape fitted within the cylindrical body between the two heads for axial confinement thereby, the internal diameter of the shell, when so positioned, being such as to press against the outer cylindrical surface of a carboy when fitted therewithin and to engage therewith substantially continuously both circumferentially and for a substantial portion of its length, spacer means positioned between the shell and the surrounding cylindrical body acting to separate one from the other whereby to provide a space therebetween permitting either the walls of the container or the shell to move therein, one toward the other, without communicating motion therebetween throughout the area where engagement obtains between the shell and carboy, and cushion means interposed between the carboy bottom and the bottom head of the container.
